UNITED STATES PATENT OFFICE.

CHARLES L. GOODRUM, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,319,999.

Specification of Letters Patent. Patented Oct. 28, 1919.

Application filed December 29, 1916. Serial No. 139,577.

To all whom it may concern:

- Be it known that I, CHARLES L. GOODRUM, a citizen of the United States, residing at New York, in the county of New York and 5 State of New York, have invented certain new and useful Improvements in Telephone-Exchange Systems, of which the following is a full, clear, concise, and exact description.
- 10 This invention relates to telephone exchange systems and more particularly to those in which automatic switches are employed in extending connections from calling lines to called lines.
- 15 The object of this invention is to provide in a full automatic system means whereby a calling subscriber who has built up a connection may make connection with an operator without releasing the automatic switches 20 employed in making the original connection.
- In accordance with this invention, after the switches are set, an electromagnetic responsive device is automatically connected through an auxiliary switching mechanism 25 to a contact of the stepping relay. If at any time thereafter the subscriber desires the attention of an operator, he causes the operation of the stepping relay which completes the circuit for said electromagnetic responsive device. The stepping relay may be operated by manipulating the finger dial at 30 the calling station.
- The electromagnetic responsive device, when actuated, causes the operation of any 35 desired signaling device, such as an alarm bell or a lamp before an operator. Provision is also made for removing the control of the signaling device when operated from the subscriber and vesting it in the operator.
- 40 The accompanying drawing shows diagrammatically a connection between two subscribers, the circuits of a connector switch embodying the principles of this invention being shown in full.
- 45 A calling subscriber's substation is shown at A, connected through a line finder indicated diagrammatically at 3, and a first selector switch shown at 4 to the connector switch having brushes 14 and 16. B indicates the substation of a called subscriber.
- The invention will be more readily understood from a consideration of the following description of the operation of the system.
- When the subscriber at A removes his receiver from the hook the line finder 3 automatically connects his line to a first selector switch 4. The subscriber now sends with his dial a series of impulses which sets the switch 4 on the terminals leading to the connector switch in whose contact bank terminates the line of the desired subscriber. As soon as the switch 4 has been set a circuit is closed from grounded battery through the retardation coil RC, lower brush of switch 3, 55 substation A, upper brush of switch 3, upper brush of switch 4, through the winding of the stepping relay SR, to ground. The relay SR is energized and closes a circuit for slow relay 5, from ground, armature and 60 front contact of relay SR, through the winding of relay 5, to battery and ground.
- The subscriber now sends a second series of impulses which causes the armature of the relay SR to vibrate. Each time relay 65 SR retracts its armature a circuit is closed from ground, armature and back contact of relay SR, right-hand armature and front contact of relay 5, wire 12, inner right hand armature and back contact of relay TR, 70 side-switch wiper 9 (position 1), through the winding of the primary magnet PM, to battery and ground. The magnet PM, as a 75 result of these impulses, steps the wipers 14 and 16 to the group of terminals in which the line of the called subscriber terminates. A circuit is also closed in parallel with that of the primary magnet, from ground, armature and back contact of relay SR, right-hand armature and front contact of relay 5, 80 through the winding of slow relay 6, to battery, and ground. Relay 6 closes a circuit, from ground, left-hand armature and front contact of relay 6, through the winding of the side-switch escape magnet Esc., to battery and ground. The magnet Esc. is held energized over this circuit during the sending of the series of impulses. At the close 85 of this series of impulses, however, the circuit for relay 6 is maintained open at the 90
- 95 100

back contact and right-hand armature of relay SR and relay 6 in deenergizing breaks at its left-hand armature the circuit for magnet Esc., which thereupon deenergizes and 5 moves the side-switch wipers into their second position.

The subscriber now sends the final series of impulses. Each time that the relay SR is deenergized a circuit is closed for the secondary magnet from ground, armature and back contact of relay SR, right-hand armature and front contact of relay 5, wire 12, inner right-hand armature and back contact of relay TR, side-switch wiper 9 (position 2), through the winding of the secondary magnet SM, to battery, and ground. The magnet SM sets the brushes of the connector switch on the terminals of the wanted line.

20 If the wanted line is busy as a calling line, battery will be supplied through the retardation coil of some line finder through brush 16 of the connector switch to wire 2. If busy as a called line, battery will be supplied to 25 wire 2 through the ringing relay RR of the connector switch associated with the wanted line, side-switch wiper 11, and brush 16 of said connector, through a multiple connection to the brush 16 of the connector of the 30 calling line. In either case a circuit for the test relay TR will be completed from battery, brush 16, wire 2, wiper 11 (position 2) right-hand winding of relay TR, front contact and armature of magnet Esc., back contact 35 and left-hand armature of relay 6, to ground. Relay TR locks up from grounded battery, through its left-hand winding, left-hand armature and front contact of relay TR, wire 19, front contact and right-hand armature 40 of relay 5, to ground. Relay TR closes in parallel with this circuit a locking circuit for the magnet Esc., from ground, right-hand armature and front contact of relay 5, wire 19, front contact and armature of relay 45 TR, wiper 8 (position 2) through the winding of magnet Esc., to battery, and ground. The continued energization of magnet Esc. will thus prevent the advance of the side switch into its third position when the called 50 line is found busy. Relay TR also closes a circuit from ground through the secondary winding of the transformer Bz, outer right-hand armature and front contact of relay TR, wire 20, line wire 1, brushes 4 and 3, 55 substation A, through the winding of the coil RC to battery, and ground.

60 The subscriber receives, as the result of this circuit a distinctive busy tone and hangs up his receiver, causing the release of the switch in a manner to be described.

Assuming now that the called subscriber's line is found idle, no circuit will be completed for the test relay TR and the magnet Esc. will, at the conclusion of the last series

of impulses, deenergize and advance the side switch into its third position. In this position a circuit is completed from battery, through the winding of ringing relay RR, wiper 11 (position 3), wire 2, brush 16, through the winding of the called line cut-off relay CO, to ground. The relay RR in attracting its armature completes a circuit for ringing the bell of the called subscriber, from grounded battery, through the generator G, winding of the ringing trip relay 7, armature and front contact of relay RR, side-switch wiper 10 (position 3), wire 1, brush 14, substation B, through the winding of the relay CO, to ground. The ringing trip relay 7 is marginal and will not be energized in this circuit. In position 3 of the side switch a circuit for the magnet Esc. was also completed from ground, left-hand armature and front contact of relay 5, wire 19, back contact and armature of relay 7, side-switch wiper 8 (position 3), through the winding of magnet Esc., to battery and ground.

If, at this time, a calling subscriber becomes impatient and desires a connection with an operator, he may, by dialing, vibrate the armature of the stepping relay SR, which, in retracting its armature, will complete a circuit from ground, armature and back contact of relay SR, right-hand armature and front contact of relay 5, wire 12, inner right-hand armature and back contact of the relay TR, side-switch wiper 9 (position 3), through the right-hand winding of the relay 13, to battery, and ground. Relay 13 completes a circuit from ground, front contact and right-hand armature of relay 13, through a signal lamp L at the central office, to battery and ground. Relay 13 also establishes a locking circuit for itself from ground, through its left-hand armature and front contact, its left-hand winding, wire 15, right-hand armature and back contact of relay CS, off-normal contact ON, through the winding of the release magnet Rel., to battery and ground. The release magnet Rel. is marginal, however, and will not energize in series with the left winding of relay 13.

It is to be understood that an alarm bell, or any other suitable signal, might be substituted for the lamp L. The operator receiving the signal inserts a plug (not shown) into the jack J, and the subscriber may now converse with the operator. The operator's signal will be actuated continuously until by answering she closes a circuit from ground, through the called supervisory relay CS, wire 1, jack J, operator's head set (not shown) to the wire 2, and through the winding of the relay RR, to battery, and ground. The called supervisory relay is energized in this circuit and breaks at its right-hand armature and front contact the previously traced locking circuit for the relay 13, which

thereupon retracts its armatures and discontinues the signal.

When the called subscriber answers, the closure of his hook switch so lowers the resistance of the ringing circuit, previously traced, as to cause the energization of the ringing trip relay 7. The ringing trip relay 7, in attracting its armature, breaks at its back contact the locking circuit for the magnet net Esc., which thereupon deenergizes and advances the side switch into its fourth position. A connection is now complete for conversation between substations A and B, the talking current for A being supplied 10 through the retardation coil RC and the stepping relay SR, while current for station B is supplied from the called supervisory relay CS and the ringing relay RR. The relay CS will be held energized until the 15 called subscriber hangs up.

If, at any time during the conversation the calling subscriber desires the attention of an operator, he may, by dialing, cause the energization of the relay 13 over a circuit 20 which is the same as that previously traced with the exception that the side-switch wiper 9 is in its fourth position instead of its third. It will be noted that the subscriber in so operating his dial will not cause the release of his switches, since the relay 5 is made slow enough to remain energized during the vibration of the armature of the stepping relay SR.

At the close of the conversation release of 25 the line finder and selectors may be accomplished by the calling subscriber alone, but the connector will not be released until both parties have hung up. If the calling subscriber is the first to hang up, the deenergization of the relay SR will complete a circuit, previously traced, for energizing slow relay 6. Slow relay 5 is a little faster than slow relay 6 and will fall off first, completing a circuit from ground, at its left-hand 30 armature and back contact through the right-hand armature and front contact of relay 6, the front contact and armature of the called supervisory relay CS through the wire 2 to the release magnets of the line 35 finder and selector switches. The ground thus applied to the wire 2 will cause the release of the line finder and selector switches in the well-known manner. When both subscribers hang up simultaneously, or the 40 called subscriber is the first to replace his receiver on its hook, ground will be placed on wire 2 from the armature and back contact of relay SR, right-hand armature and back contact of relay 5, back contact and 45 left-hand armature of relay CS to wire 2, thus closing the release circuit for the line finder and selector switches. A circuit is also closed from ground, left-hand armature and back contact of relay 5, wire 15, right-

hand armature and back contact of relay CS. 65 off-normal contact ON, through the winding of the release magnet Rel., to battery and ground. The placing of a ground on the wire 2 renders the connector switch immediately selectable, but the return of the 70 switch to normal is insured, since the release magnet is locked up from battery, through its winding, off-normal contact ON, armature and front contact of magnet Rel., to ground. This locking circuit will be 75 broken the restoration of the switch to normal opens contact ON and the system is in readiness for another call.

Although the invention has been shown applied to switches of the two-wire multiple 80 trunk type, it is to be understood that its principles may be readily applied to any well-known type of automatic switches.

What is claimed is:

1. In a telephone exchange system, telephone lines, automatic switches including a connector switch for interconnecting said lines, a device for signaling an operator, an electromagnetic responsive device permanently associated with said connector switch 85 for operating said signaling device, and means operable by a calling party when a connection has been built up over said switches for actuating said electromagnetic responsive device. 90

2. In a telephone exchange system, telephone lines, automatic switches for interconnecting said lines, means including a stepping relay for setting said switches, means operable by a calling party for actuating said stepping relay, a device for signaling an operator, an electromagnetic responsive device controlled by said stepping relay for operating said signaling device, and an auxiliary switching mechanism 100 for operatively connecting said electromagnetic responsive device to said stepping relay when said switches have been set. 105

3. In a telephone exchange system, telephone lines, automatic switches including a connector switch for interconnecting said lines, a device for signaling an operator, an electromagnetic responsive device permanently associated with said connector switch 110 for operating said signaling device, means operable by a calling party when a connection has been built up over said switches for actuating said electromagnetic responsive device, and means for automatically removing control of said electromagnetic responsive device when operated from said calling party and vesting such control in said operator. 115

4. In a telephone exchange system, telephone lines, automatic switches for interconnecting said lines, means including a stepping relay for setting said switches, means operable by a calling party for actuating 120

said stepping relay, a device for signaling an operator, an electromagnetic responsive device controlled by said stepping relay for operating said signaling device, an auxiliary 5 switching mechanism for operatively connecting said electromagnetic responsive device to said stepping relay when said switches have been set, and means for auto-

matically removing control of said electromagnetic responsive device when operated 10 from said calling party and vesting such control in said operator.

In witness whereof, I hereunto subscribe my name this 28th day of December A. D., 1916.

CHARLES L. GOODRUM.
